UNITED STATES PATENT OFFICE.

PETER W. SPRECHER, OF MILWAUKEE, WISCONSIN.

ELECTRIC-FIXTURE HANGER.

Application filed October 30, 1922. Serial No. 597,838.

To all whom it may concern:

Be it known that I, PETER W. SPRECHER, a citizen of the United States, and resident of Milwaukee, in the county of Milwaukee, 5 and State of Wisconsin, have invented certain new and useful Improvements in Electric-Fixture Hangers; and I do hereby declare that the following is a full, clear, and exact description thereof.

10 The invention relates to electric fixture hangers of the type which are adapted to be secured to the ceiling or side wall of a room to support an electric fixture therefrom.

A general object of the invention is to 15 simplify and otherwise improve the construction of such devices, whereby they may be manufactured at a minimum expense and easily installed.

The invention comprises a canopy and a 20 block of insulation in a tapered head of the canopy covered by the canopy.

It is an object of the construction to have 25 a hanger of especially ornate appearance. This results from the fact that the canopy is of one piece, there being no additional exterior depending block or portion. The block serves also as a guide for a screw adapted to be threaded in a hickey. This 30 feature is especially advantageous, in view of the fact that ease of assembly of parts and readiness of installation are important with hangers of this general type. Considerable difficulty has heretofore been experienced in the accurate setting of the 35 screw.

An important object of the block construction is the protection of wires from the 40 edges of the canopy, preventing cutting of the insulation on the wires. The canopy is provided with openings through which the 45 wires are threaded and these openings are large as compared with openings in the block, so that possibility of cutting is eliminated. The construction is of general utility, being adapted for insulated or grounding fixtures.

With the above and other objects in view, 50 which will appear as the description proceeds, my invention resides in the novel construction, combination and arrangement of parts substantially as hereinafter described and more particularly defined by the appended claim, it being understood that such changes in the precise embodiment of 55 the herein disclosed invention may be made as come within the scope of the claim.

In the accompanying drawing, I have illustrated one complete example of the physical embodiment of the present invention constructed according to the best mode. 60 I have so far devised for the practical application of the principles thereof, and in which:

Figure 1 represents a sectional view 65 through an outlet box with the invention attached thereto.

Figure 2 is a bottom plan of the lower 70 end of the device, and

Figure 3 is a bottom plan of a modified 75 structure.

Referring in detail to the drawing, the 80 numeral 5 indicates the ceiling or wall of a room, in which an outlet box 6 is embedded, connected with which is a conduit 7 through which the wires 8 are introduced. A supporting stud 9 is secured centrally of the outlet box and a suitable hickey 10 is attached thereto. The canopy 11 is secured 85 so as to enclose the outlet box. This canopy is preferably made from one piece of sheet metal pressed into the shape illustrated with an elongated lower portion 12, which terminates in a flat end portion 13. A screw 14 of suitable length is passed centrally through the end 13 and threaded into the hickey 10. This screw is surrounded by a spacing 90 sleeve 15, preferably of insulating material, which abuts at its upper end against the hickey and is received in its lower end in a recess in insulating block 16, which conforms to the shape of the lower end of the canopy. The insulating block is provided with an annular collar 17 adapted to rest 95 against a shoulder formed in the canopy. The pressure of screw 14 maintains the canopy snugly in position against block 16.

Thus it will be seen that a strong and durable support is formed for the suspension ring 19, the ends of which are directed 100 through openings in the canopy and received in recesses in the insulating block. The ring supports a chain pendant 20, or other form of electric light fixture. The end portion 13 of the canopy is also provided with a suitable number of openings 105 21, through which the wires may pass to the light. Block 16 is provided with longitudinal channels for the wires and the openings 21 are somewhat larger than the channels so that there is no danger of a cutting 110 action being produced by the edge of the canopy upon the wires.

The ease of installation of the device is apparent, as block 16 and sleeve 15 provide means for readily centering the screw with respect to the hickey.

5 Block 16 is substantially invisible to the eye, being almost completely covered by the canopy so that the hanger presents a very attractive appearance.

10 In the modification shown in Figure 3 the screw does not contact with the end portion of the canopy, but its head is entirely insulated by the block, the end of the canopy being cut away so as to form a pair of substantially semi-circular flanges 22—22'. In 15 this modification the screw is not operative directly to maintain the canopy in position. The canopy is supported by the upper ends of ring 19 which extends into the block, the block in turn being retained securely in position by the screw.

20 I claim:—

In an electric fixture the combination of a

supporting hickey having a threaded lower aperture, a canopy, an insulating block located within said canopy at its lower end, a 25 screw passing through the lower portion of said canopy and through said insulating block and threaded through the aperture in said hickey, a spacing sleeve positioned within said hickey and said insulating block 30 and adapted to force said insulating block into intimate engagement with the inner portion of said canopy when said screw is tightened, said canopy and said block having aligning apertures through which electric leads may be passed, and a supporting ring extending through apertures in said canopy into said insulating block.

35 In testimony that I claim the foregoing I have hereunto set my hand at Milwaukee, 40 in the county of Milwaukee and State of Wisconsin.

PETER W. SPRECHER.
